SAND HANDLING APPARATUS

Walter F. Piper, Oak Park, Ill., assignor to The
Beardsley & Piper Company, Chicago, Ill., a
corporation of Illinois

Application December 19, 1931, Serial No. 582,053

14 Claims. (Cl. 209—326)

The present invention relates generally to apparatus for riddling and feeding granular material. More particularly the invention relates to that type of riddling and feeding apparatus which has special utility in connection with the handling of molding sand and comprises a riddle equipped chute or hopper and motor driven mechanism for operating or shaking the hopper for sand riddling and feeding purposes.

One object of the invention is to provide an apparatus of this type which is more efficient in operation than previously designed apparatus for the same purpose by reason of the fact that the mechanism for operating the riddle-equipped chute comprises a shaft which is rotatably and eccentrically mounted in a motor driven fly wheel or like element to rotate bodily in an upwardly inclined circular path and is connected at its upper end to the chute so that during rotation of the fly wheel it moves the chute or the portion of the chute to which it is connected in a corresponding upwardly inclined circular path and causes the sand to advance or move over the riddle with a hopping action due to the vertical and lateral shift of the chute out of its normal position or plane.

Another object of the invention is to provide a sand riddling and feeding apparatus which is generally of new and improved construction and is adapted to be driven or operated at high speed without excessive wear and vibration of the various parts thereof.

Other objects of the invention will be apparent from a consideration of the following detailed description.

The invention consists in the several novel features which are hereinafter set forth and are defined more particularly by claims at the conclusion hereof.

In the drawings which accompany and form a part of this specification or disclosure and in which like numerals of reference denote corresponding parts throughout the several views: Fig. 1 is a side elevation of a sand projecting machine having mounted thereon an apparatus embodying the invention. Fig. 2 is an enlarged section through the mechanism for operating the riddle-equipped feed chute. Fig. 3 is a horizontal section on the line 3—3 of Fig. 2. Fig. 4 is a section on the line 4—4 of Fig. 2. Fig. 5 is a section on the line 5—5 of Fig. 2. Fig. 6 is a section on the line 6—6 of Fig. 1. Fig. 7 is a side elevation of the supporting strut for the front or discharge end of the chute, parts being shown in section.

The apparatus which forms the subject matter of the invention is designed primarily for use in riddling and feeding molding sand and comprises a chute or hopper 10 and mechanism for operating or shaking the chute. As shown in Figs. 6 and 7, the chute is provided with a riddle 11 for screening or riddling the sand delivered to the chute. The screen separates the scrap metal from the sand delivered to the chute, and discharges it laterally through an outlet 12. The screen also serves to cut or disintegrate the lumps of sand and to mix it in transit to the mold. The chute and its operating mechanism are mounted to move laterally with an arm 13 which is pivoted on a standard 14. The sand is delivered into one end of the chute and is discharged at the other end thereof. A second arm 9 is pivoted to the outer end of arm 13 and carries a rotary projector 8 for slinging the sand into molds, as exemplified in Patent No. 1,408,493. The sand discharged from the chute 10 is delivered onto a feed belt 9^a which delivers the sand to the projector. The chute is operated or vibrated by the mechanism hereinafter described to screen the sand and discharge it at 15 onto the belt 9^a. Arms 13 and 9 permit the projector 8 to be moved horizontally over molds so that all portions thereof can be rammed with sand.

The mechanism for shaking or operating the chute is supported by a bracket 16 which is bolted to a sleeve 11 to which the inner end of arm 13 is secured. Bracket 16 comprises an annulus 16^a and an upwardly inclined lateral extension 18 in which is secured a fixed shaft 19. A cover 16^b is bolted to the top of the annulus 16^a. An electric motor 20 for driving the gearing for vibrating the chute is secured to the outer end of extension 18. Shaft 19 is pressed into a socket 18^a, and serves to support a fly-wheel 21 for rotation on an axis which is fixed relatively to the supporting bracket. The hub of wheel 21 has a central socket 22 into which the shaft 19 extends and is journaled on roller bearings 23 which are disposed in said socket and around said shaft. A collar 19^a, fixed on shaft 19 between the inner members of the roller bearings, holds them in spaced relation so the fly wheel will be held against vertical movement on the shaft 19. A screw ring 24 closes the lower end of socket 22 and carries a packing ring 22^a to exclude sand from and retain lubricant in said socket. The fly wheel is driven by a pinion 25 which is fixed to the armature shaft of motor 20 and a gear ring 26 which is disposed around the hub of the fly wheel and is secured

by bolts 28 to a flange 27 integral with the hub.

The fly-wheel 21 is provided with a depending flange 21^a and has a top wall 21^b to enclose or cover the driving gears. The upper portion 21^c of the hub of the fly wheel is eccentric to the axis of the shaft 19 around which the fly-wheel rotates and has an eccentric socket 29 in which is journalled a shaft or wrist-pin 30 which has its axis parallel to, but eccentric relatively to the fixed shaft 19. Roller bearings 31 are mounted in socket 29 between shaft 30 and the hub 21^c. A spacing collar 30^a is fixed to shaft 30 between bearings 31 to hold the shaft against axial movement relatively to the fly-wheel. A screw-ring 32 closes the upper end of socket 29 and carries a packing ring 33 to exclude dust from and retain lubricant in said socket. A duct 34, which is closed by a screw-plug 35, is provided in the hub of the fly-wheel for delivering lubricant into the sockets 22 and 29 which communicate with each other. A duct 34^a is also formed in the hub of the fly wheel and is closed at its lower end by a fitting 34^b through which grease may be forced into the sockets. Lugs 36, each held by a screw 37, are adapted to lock the screw-rings 24 and 32 against becoming loose. A circular cover plate 38 is secured by a bolt 39 to the upwardly projecting end of eccentric shaft 30 to exclude sand from the top of the fly wheel and around shaft 30. The fly-wheel is provided with a weighted portion 21^d to counterbalance the eccentric hub and cause it to rotate smoothly at high speed.

A transversely extending saddle bar 40 is fixed to the upper end of the eccentric shaft 30, and a bushing 40^a which is semi-circular in cross section is secured in said bar. Said bushing has a cylindrical seat for a cylindrical bearing-rod 41 which is welded to a reinforcing plate 42 which is riveted to the bottom of chute 10. Bolts 43 pass through rod 41 and slots 44 in bar 40 and bushing 40^a and hold the chute seated in the bushing and against transverse movement, while permitting relative longitudinal, pivotal movement of the chute. The discharge end of the chute is supported by a strut rod 46. The upper end of rod 46 terminates in a bearing ball 46^a, and a bearing 47 with a ball socket seats on said ball to provide a bearing which permits relative pivotal movements of the chute and said rod. Bearing 47 is confined in a sleeve 48 which is welded to a reinforcing plate 10^d on the chute 10. A bolt 49 extends through sleeve 48 and a slot 46^b in the rod 46 to hold the socket seated on ball 46^a without interfering with the relative pivotal movements of the chute and the rod. The lower end of rod 46 is clamped by bolts 50 and plate 51 to the upper end of a transversely extending cushion plate 52 which is formed of rubber and extends transversely sufficiently to hold yieldingly the rod 46 against substantially transverse movement, while permitting the rod to swing longitudinally of the chute, the cushion being readily transversely flexible for this purpose. The lower end of cushion 52 is clamped by bolts 53 and a plate 54 in a bracket 55 which is secured by a bolt 56 to the tubular supporting arm 13.

The bottom wall of chute 10 and screen 11, as illustrated in Fig. 2, extend substantially in horizontal planes when the chute reaches the limit of its forward stroke. The parallel axes of eccentric shaft 30 and fixed shaft 19 are inclined relatively to the bottom of the chute to cause the saddle, which supports the delivery end of the

chute 10, to move back and forth in an inclined plane. The axis of the strut-rod 46 which support the discharge end of the chute is also inclined and approximately parallel to the axis of the shaft 30. When the motor is running, the fly-wheel will be rotated on the fixed shaft 19, and eccentric shaft 30, will be shifted bodily in a circular path. This circular movement of the shaft 30 will impart a corresponding movement to the delivery end of the chute, so the latter will be shifted laterally and longitudinally. The shaft 30 moves in a circular plane which is inclined relatively to the bottom of the chute to cause the bottom of the chute and the screen to be shifted from an inclined plane to a substantially horizontal position during the outstroke of the chute. The impulses imparted to the material by the movements of the chute will cause the sand to be projected forwardly with a hopping action and discharged at 15 from the chute. This may, if desired, be accomplished by the mechanism described without bringing the chute into a downward inclination toward its discharge end. The lateral movement imparted to the chute by the fly-wheel and eccentric shaft 30 causes the sand to be spread transversely across the chute, and this results in efficiently and speedily riddling the sand, and makes it possible to feed the large volumes of sand required for a sand projector. The rod 46 and its ball bearing pivotally support the discharge end of the chute to permit longitudinal and transverse movement of the delivery end by the eccentric shaft, and serve further to prevent the chute from rotating bodily around the fly-wheel during drive of the latter.

In cutting and feeding molding sand at the desired rate to keep the projector supplied for high speed sand slinging, it is necessary to operate the chute at high speeds. According to the present invention, the rotating elements can be operated at high speeds, smoothly and evenly to operate the chute in a path which is efficient in feeding and screening the sand. The discharge end of the chute is cushioned so practically no vibration will be imparted to the outer end of the supporting arm 13 by the discharge end of the chute. As a result the apparatus has been found in practice to operate smoothly at high speeds without causing destructive vibration in the arms for supporting the projector, and this eliminates wear which results from such vibration.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In apparatus of the character described, the combination of a horizontally extending, riddle-equipped chute for receiving granular material, and mechanism for operating the chute for material riddling purposes comprising a rotatable shaft disposed beneath one end of the chute and mounted to revolve bodily in an upwardly inclined circular path, a connection between the upper end of the shaft and said one end of the chute whereby the said one end of the chute will be shifted in a corresponding upwardly inclined circular path by the shaft, and the chute will be shifted vertically and laterally out of the normal plane thereof and the material therein will be advanced with respect to the riddle with a hopping 75

action, and mechanism for revolving said shaft in the aforementioned path.

2. In an apparatus of the character described, the combination of a horizontal, material-receiving chute, and mechanism for operating the chute comprising an upwardly inclined shaft having a fixed axis, a rotatable flywheel on the shaft, a second shaft mounted rotatably and eccentrically in the wheel and projecting upwardly from the latter, said second shaft being parallel with the first mentioned shaft and adapted to revolve bodily in an upwardly inclined circular path during rotation of the flywheel, a connection between the upper end of said second shaft and one end of the chute whereby said one end of the chute will be shifted in a corresponding upwardly inclined circular path by the eccentric shaft, and the chute will be shifted vertically and laterally out of the normal plane thereof and the material therein will be advanced with a hopping action, mechanism for driving the flywheel, and a pivotal support for the other end of the chute.

3. In apparatus of the character described, the combination with a horizontal material-receiving element mounted to swing vertically, of mechanism for shifting said element comprising an upstanding shaft with a rotatable fixed axis, a wheel on said shaft, mechanism for driving said wheel, a rotatable shaft eccentrically rotatably mounted in the wheel and operable in a circular path by the rotation of the wheel, and a connection between the eccentric shaft and the element whereby a portion of the element will be operated in a circular path by the eccentric shaft and supported to swing vertically, said connection comprising a transversely extending saddle attached directly to the eccentric shaft and a bearing bar in the saddle and applied to the element for holding the eccentric shaft and the element against relative rotation.

4. Mechanism for shifting a chute, comprising in combination an upstanding shaft having a fixed axis, a fly-wheel mounted on said shaft, gearing directly beneath the fly-wheel for driving the latter, a depending annular flange on the fly-wheel for enclosing said gearing, a shaft eccentrically mounted in the upper part of the fly-wheel and bodily rotatable in a circular path by rotation of the wheel, and means associated with the upper end of the eccentric shaft for attachment to the chute.

5. In apparatus of the character described, the combination with an arm pivoted to swing horizontally, and a chute and riddle movable laterally with said arm, of mechanism for shifting the chute, mounted on the arm and comprising an eccentric shaft mounted to move in a circular path, a connection between the chute and said shaft whereby one end of the chute will be shifted in a corresponding circular path, a cushioned pivotal support between the arm and the other end of the chute, and mechanism for moving said shaft in said circular path.

6. In apparatus of the character described, the combination with a support and a horizontally movable chute carried by said support, of mechanism for shifting the chute, mounted on the support and comprising a shaft eccentrically mounted to travel in a circular path, mechanism for moving said shaft in said circular path, a connection between the eccentric shaft and one end of the chute whereby the chute will be shifted in a corresponding circular path, and a cushioned vertical strut for pivotally supporting the other end of the chute.

7. In apparatus of the character described, the combination with a horizontally extending support and a substantially horizontal chute positioned over said support, of mechanism for shifting the chute mounted on the support and comprising a rotatable shaft eccentrically mounted to travel bodily in an upwardly inclined circular path, mechanism for moving the shaft in said circular path, a connection between the eccentric shaft and one end of the chute whereby the chute will be shifted in a corresponding circular path by the shaft during movement thereof and the element will be shifted vertically and laterally out of the normal plane thereof and material therein will be advanced with a hopping action, a strut for supporting the other end of the chute, and a ball-bearing between the strut and the chute.

8. In apparatus of the character described, the combination with a support and a substantially horizontal chute carried movably on said support, of mechanism for shifting the chute, mounted on the support and comprising a shaft eccentrically mounted to travel in a circular path, mechanism for rotating the shaft in said circular path, a connection between the eccentric shaft and one end of the chute whereby the chute will be shifted in a corresponding circular path, a strut for supporting the other end of the chute, and an elastic support for the strut.

9. In apparatus of the character described, the combination with a feed chute, of mechanism for shifting the chute comprising an eccentric shaft mounted to move in an upwardly inclined circular path, mechanism for operating said shaft, means between the chute and the shaft whereby one end of the chute will be shifted in a corresponding upwardly inclined circular path in response to operation of the shaft in order to shift the chute vertically and laterally to advance material therein with a hopping action, said chute being pivoted to swing vertically and transversely to the plane of said circular path, and a pivotal support for the other end of the chute which permits universal movement of the chute.

10. In apparatus of the character described, the combination with a feed chute, of mechanism for shifting the chute comprising an eccentric shaft mounted to move in an upwardly inclined circular path, mechanism for operating said shaft, means between the chute and the shaft whereby one end of the chute will be shifted in a corresponding upwardly inclined circular path in response to operation of the shaft in order to shift the chute vertically and laterally, said chute being pivoted to swing vertically and transversely to the plane of said circular path, a strut for supporting the other end of the chute, a universal joint between the strut and the chute, and an elastic support for the strut.

11. In apparatus of the character described, the combination with an arm pivoted to swing horizontally, and a chute and riddle movable laterally with said arm, of mechanism for shifting the chute mounted on the arm and comprising an upstanding shaft, a bracket fixed to the proximal end of the arm and to which said shaft is secured, a wheel supported on the shaft, a motor mounted on the bracket, gearing for driving said wheel from the motor, a shaft rotatably supported by the wheel and eccentrically mounted in the wheel to travel in a circular path, and a connection between the eccentric shaft and the chute, whereby the chute will be supported and shifted.

in a corresponding circular path in response to drive of the wheel.

12. In apparatus of the character described, the combination with an arm pivoted to swing horizontally, and a chute and riddle movable laterally with said arm, of mechanism for shifting the chute mounted on the arm and comprising an upstanding shaft, a bracket fixed to the proximal end of the arm and to which said shaft is secured, a wheel supported on the shaft, a motor mounted on the bracket, gearing for driving said wheel from the motor, a shaft rotatably supported by the wheel and eccentrically mounted in the wheel to travel in a circular path, and a connection 10 between the eccentric shaft and the chute whereby the chute will be supported and shifted in a corresponding circular path in response to drive of the wheel, said connection comprising means for permitting the chute to swing vertically relatively to the eccentric shaft.
13. In combination, a substantially horizontal riddle-equipped chute for receiving granular material, and mechanism for operating or shaking the chute for material riddling purposes, comprising an inclined rotatable shaft disposed under the chute and mounted to revolve bodily in an upwardly inclined circular path, a connection between the upper end of the shaft and said chute whereby the chute will be shifted in a corresponding 20 upwardly inclined circular path by the shaft and the material will be moved with respect to the

riddle with a hopping action as the result of the combined vertical and lateral displacement of the chute out of its normal plane, mechanism for revolving said shaft in the aforementioned path, and means for preventing the chute from swinging bodily around the shaft when it is shifted or operated by the latter.

14. In combination, a substantially horizontal material receiving chute, and mechanism for operating the chute for material shaking purposes comprising an upwardly inclined shaft having a fixed axis, a rotatable member on the shaft, a second shaft mounted rotatably and eccentrically in said member and projecting upwardly from the latter, said second shaft being parallel 15 with the first mentioned shaft and adapted to revolve bodily in an upwardly inclined circular path during rotation of the member, a connection between the upper end of said second shaft and the chute whereby the chute will be shifted in a corresponding upwardly inclined circular path by the eccentric shaft and the material therein will be moved with a hopping action as the result of the combined vertical and lateral displacement of the chute out of the normal plane or position 20 thereof, means applied to one end of the chute for preventing the chute from swinging bodily around said second shaft during shift by the latter, and means for driving the rotatable member.

30
